DISCHARGE OUTLET COVER PLATE

Clarence J. Koranda, Western Springs, and Harry A. Withall, Chicago, Ill., assignors to Enterprise Railway Equipment Company, Chicago, Ill., a corporation of Illinois

Application February 2, 1955, Serial No. 485,789

5 Claims. (Cl. 105—282)

This invention relates, generally, to discharge outlets for hoppers for railway cars, trucks and the like and it has particular relation to the attachment thereto of a sanitary plate used to prevent contamination of the interior of the discharge valve housing of the hopper and the underside of the movable gate which controls the flow of lading therethrough.

Among the objects of this invention are: To provide simple, efficient and economical means for holding a removable sanitary plate in place on the underside of a discharge valve of a lading containing hopper; to hold the plate in place by wedging action; to employ a locking bar wedgingly supported at its ends for underlying the plate and holding it in closed position; to support the locking bar by a stationary keeper at one end and a pivoted keeper at the other; to provide cooperating engaging wedging surfaces on the keepers and the respective ends of the locking bar; to hold the locking bar in place by a removable locking pin; and to provide for applying torque to the pivoted keeper for swinging it toward the stationary keeper and wedging the plate into closed position.

Other objects of this invention will, in part, be obvious and in part appear hereinafter.

This invention is disclosed in the embodiment thereof shown in the accompanying drawing and it comprises the features of construction, combination of elements and arrangement of parts which will be exemplified in the construction hereinafter set forth and the scope of the application of which will be indicated in the appended claims.

For a more complete understanding of the nature and scope of this invention reference can be had to the following detailed description, taken together with the accompanying drawing in which:

Figure 1 is horizontal sectional view taken generally along the line 1—1 of Figure 2 and showing the housing which is located on the underside of the discharge valve for a load containing hopper;

Figure 2 is a longitudinal sectional view taken generally along the line 2—2 of Figure 1;

Figure 3 is a vertical transverse sectional view taken generally along the line 3—3 of Figure 1; and

Figure 4 is a fragmentary view in end elevation of the construction as shown in Figure 1, the view being taken from the left hand end of this figure and looking from left to right.

Referring to the drawing, it will be observed that the reference character 10 designates a rectangular steel or cast iron housing which is located around a discharge opening 11 of a discharge valve for a load containing hopper. It will be understood that the housing 10 discharges downwardly and that the discharge of the lading from the hopper is controlled by a slideable gate (not shown) or other suitable valve means well known in the art. The present invention has to do with the protection of the underside of such a gate and the interior of the housing 10 from contamination. This is important when the hop-

2

per with which the housing 10 is associated is employed for transporting flour, sugar or the like.

Extending outwardly from the lower edge of the housing 10 is a flange having portions 12 and 13 at the ends 5 and 14 and 15 at the sides as shown more clearly in Figure 1. Against the undersides of these flange portions there is positioned a removable sanitary plate 16. Interposed between the upper surface of plate 16 and the under surfaces of the flange portions is a gasket 17. It 10 will be observed that the flange portions 13 and 15 are provided with inwardly opening slots 19 and 21 for receiving the corresponding edges of the sanitary plate 16 and also for receiving a detachable connection to a conveying conduit which is applied to the housing 10 in lieu 15 of the plate 16 for unloading purposes.

The underside of the sanitary plate 16 is provided with transverse ribs 22 each having a central slot 23 for receiving a locking bar 24 that may have a square cross-section as shown more clearly in Figure 3. The upper side of the locking bar 24 bears against the underside of a longitudinally extending rib 25 that is formed integrally with the underside of the plate 16. Provision is made for wedgingly holding the plate 16 in the closed position through the agency of the locking bar 24. The details of 20 this construction will now be set forth.

In Figure 2 it will be noted that the underside 28 of the right hand end of the locking bar 24 is inclined upwardly so as to wedgingly engage an upwardly facing downwardly and inwardly inclined wall 29 of a stationary keeper 30 that is carried by the housing 10. Preferably the stationary keeper 30 is cast integrally with the housing 10, although it may be secured thereto by other means 25 as desired.

A somewhat similar construction is provided at the left hand end of the locking bar 24. Its underside 32 is inclined upwardly in order to wedgingly engage an upwardly facing downwardly and inwardly inclined wall 33 of a pivoted keeper 34. The keeper 34 has an upwardly extending arm 35 which is positioned between spaced ears 36 that project upwardly from the flange portion 12, Figure 4. A rivet 37 extends through the ears 36 and the arm 35 for pivotally mounting the keeper 34 so that it can swing toward and away from the stationary keeper 30.

With a view to employing the wedging action that is 40 provided through the agency of the interengaging undersides 28 and 32 of the locking bar 24 with the walls 29 and 33, a socket 38 is formed in the keeper 34 for receiving a removable bar that is indicated by conventional broken lines at 39. When the bar 39 is inserted in the socket 45 38 and is moved downwardly, the resultant torque applied to the keeper 34 swings it toward the stationary keeper 30 and moves the locking bar 24 upwardly to force the sanitary plate 16 into sealing engagement with the gasket 17.

50 In order to hold the locking bar 24 in operative position ears 41 are formed integrally with the keeper 34 and they extend inwardly therefrom on opposite sides of the left hand end of the locking bar 24. The ears 41 are provided with elongated apertures 42 which are arranged to register with a circular aperture 43 in the left hand end of the locking bar 24. A locking pin 44 extends transversely through the apertures 42 and 43, as shown in Figure 4, to lock the assembly in the position shown in Figure 2. A sealing strip 45 extends through one end of the pin 44 to prevent unauthorized withdrawal. A chain 46 is secured to the other end of the locking pin 44 and to a staple 47 projecting upwardly from the flange portion 12 to prevent loss of the locking pin 44 when it is withdrawn 55 from operative position.

In operation, when it is desired to remove the plate 16, the sealing band 45 is removed and the locking pin 44 is

withdrawn. This permits the pivoted keeper 34 to swing about its axis and release its end of the locking bar 24. Should difficulty be encountered in so operating the keeper 34, the removable bar 39 can be inserted in the socket 38 and the necessary torque applied to swing the keeper 34 out of engagement with the locking bar 24. The locking bar 24 then can be removed bodily from underneath the plate 16 which then is removed.

The housing 10 is closed off by applying the plate 16 after the lading has been discharged. Then the bar 24 is inserted in the keeper 30 and the keeper 34 is swung to engage the other end. The bar 39 is inserted in the socket 38 and the keeper 34 is moved toward the keeper 30 until the apertures 42 in the ears 41 register with the aperture 43 in the left hand end of the bar 24. The locking pin 44 then is inserted and the sealing band 45 applied.

Since certain changes can be made in the foregoing construction and different embodiments of the invention can be made without departing from the spirit and scope thereof, it is intended that all matter shown in the accompanying drawing and described hereinbefore shall be interpreted as illustrative and not in a limiting sense.

What is claimed as new is:

1. In a discharge valve for mounting on the underside of a hopper for a railway car or the like, in combination, a housing defining a downwardly directed discharge opening, a removable plate extending transversely across said opening for closing the same, a stationary keeper depending from one side of said housing below said plate and having an upwardly facing downwardly and inwardly inclined wall, a movable keeper pivotally mounted on and depending from the opposite side of said housing below said plate to swing toward and away from said stationary keeper and having an upwardly facing downwardly and inwardly inclined wall, a locking bar having the undersides of its ends inclined upwardly to wedgingly engage the respective inclined walls of said keepers and underlying said plate to hold the same in closed position, and means holding said locking bar in plate supporting position.

2. In a discharge valve for mounting on the underside of a hopper for a railway car or the like, in combination, a housing defining a downwardly directed discharge opening, a removable plate extending transversely across said opening for closing the same, a stationary keeper depending from one side of said housing below said plate and having an upwardly facing downwardly and inwardly inclined wall, a movable keeper pivotally mounted on and depending from the opposite side of said housing below said plate to swing toward and away from said stationary keeper and having an upwardly facing downwardly and inwardly inclined wall, a locking bar having the undersides of its ends inclined upwardly to wedgingly engage the respective inclined walls of said keepers and underlying said plate to hold the same in closed position, said movable keeper having means to which torque can be applied for swinging the same toward said stationary keeper and raising said locking bar against said plate, and means holding said locking bar in plate supporting position.

3. In a discharge valve for mounting on the underside of a hopper for a railway car or the like, in combination, a housing defining a downwardly directed discharge opening, a removable plate extending transversely across said opening for closing the same, a stationary keeper depending from one side of said housing below said plate and having an upwardly facing downwardly and inwardly in-

clined wall, a movable keeper pivotally mounted on and depending from the opposite side of said housing below said plate to swing toward and away from said stationary keeper and having an upwardly facing downwardly and inwardly inclined wall, a locking bar having the undersides of its ends inclined upwardly to wedgingly engage the respective inclined walls of said keepers and underlying said plate to hold the same in closed position, said movable keeper having a pair of apertured inwardly extending ears on opposite sides of said latch bar registering with an aperture therein, and a locking pin extending through the apertures in said ears and latch bar to hold it in plate supporting position.

4. In a discharge valve for mounting on the underside of a hopper for a railway car or the like, in combination, a housing defining a downwardly directed discharge opening, a removable plate extending transversely across said opening for closing the same, a stationary keeper depending from one side of said housing below said plate and having an upwardly facing downwardly and inwardly inclined wall, a movable keeper pivotally mounted on and depending from the opposite side of said housing below said plate to swing toward and away from said stationary keeper and having an upwardly facing downwardly and inwardly inclined wall, a locking bar having the undersides of its ends inclined upwardly to wedgingly engage the respective inclined walls of said keepers and underlying said plate to hold the same in closed position, said movable keeper having an outwardly opening socket for receiving a removable bar to apply torque to said keeper to swing it inwardly toward said stationary keeper and raise said locking bar against said plate, and means holding said locking bar in plate supporting position.

5. In a discharge valve for mounting on the underside of a hopper for a railway car or the like, in combination, a housing defining a downwardly directed discharge opening, a removable plate extending transversely across said opening for closing the same, a stationary keeper depending from one side of said housing below said plate and having an upwardly facing downwardly and inwardly inclined wall, a movable keeper pivotally mounted on and depending from the opposite side of said housing below said plate to swing toward and away from said stationary keeper and having an upwardly facing downwardly and inwardly inclined wall, a locking bar having the undersides of its ends inclined upwardly to wedgingly engage the respective inclined walls of said keepers and underlying said plate to hold the same in closed position, said movable keeper having an outwardly opening socket for receiving a removable bar to apply torque to said keeper to swing it inwardly toward said stationary keeper and raise said locking bar against said plate, said movable keeper having a pair of apertured inwardly extending ears on opposite sides of said latch bar registering with an aperture therein, and a locking pin extending through the apertures in said ears and latch bar to hold it in plate supporting position.
